(57) **CLAIM**

The ornamental design for a fin ornament, as shown and described.

DESCRIPTION

FIG. 1 is a perspective view of the fin ornament;

FIG. 2 is a right elevation view thereof, the left elevation view being a mirror image thereof;

FIG. 3 is a top plan view thereof;

FIG. 4 is a front elevation view thereof;

FIG. 5 is a rear elevation view thereof;

FIG. 6 is a bottom plan view thereof; and,

FIG. 7 is a perspective view.

In the drawings, the broken lines in FIG. 7 depict a n automobile, and optional fin ornament placement only and form no part of the claimed design.
